Patented Feb. 17, 1920.

UNITED STATES PATENT OFFICE.

ALBERT V. RACKSTRAW, OF BEDFORD, OHIO.

ENDLESS LINK-CHAIN TRACK.

1,331,080.

Specification of Letters Patent. Patented Feb. 17, 1920.

Application filed May 27, 1919. Serial No. 300,104.

To all whom it may concern:

Be it known that I, ALBERT V. RACKSTRAW, a subject of the King of Great Britain, residing at Bedford, in the county of Cuyahoga and State of Ohio, have invented certain new and useful Improvements in Endless Link-Chain Tracks, of which the following is a specification.

This invention relates to new and useful improvements in endless, self-laying tracks employing articulated link sections, and used on motor vehicles, particularly of the tractor type.

Ordinarily these flexible endless tracks comprise a series of steel links connected by case-hardened steel pivot pins. Inasmuch as tractors are subjected to very heavy wear, the tracks often being submerged in mud, there is naturally severe strain on the elements, and a clogging or encumbering of said elements with mud or other extraneous matter.

The primary object of the present invention is the provision of a simple and durable track of the character set forth, which will run smoothly, and in which there is little or no lost motion, and in which the liability to become clogged is reduced to a minimum.

With these and other apparent objects in view, the invention consists essentially, in the novel and peculiar combination of parts and details of construction as hereinafter set forth and described and pointed out definitely in the appended claims, reference being had to the accompanying drawing which is made part of the specification, similar reference characters being employed to designate corresponding parts.

In the said drawing Figure 1 is a side elevation of two link units as connected in the chain.

Fig. 2 is a plan view of two of the said units connected.

Fig. 3 is a right hand end view of one unit, and Fig. 4 is a section of one unit taken on line 4—4 of Fig. 3.

Tracks of this class generally comprise an endless chain, or an articulated member adapted to be engaged by a driven sprocket. The present invention consists in the novel particular construction of the units 10, a plurality of said units being pivotally connected and adapted to cooperate with a driven sprocket.

In the embodiment as illustrated, each in-

dividual unit 10 is an integral casting which comprises a plate 11, said plate performing the function of a shoe or tread, on which the structure is supported. The tread member 11 is provided with a transverse traction flange 12 on one end thereof, and the opposite end has a medial recess 13 therein.

Two ears 14 and 15 extend vertically from the member 11, and are spaced equi-distant from the longitudinal medial line and in juxtaposition to the notched, or recessed end of said member 11, as shown. These ears 14 and 15 combined form the female portion of the link. The opposite or flanged end of the plate 11 is provided with a male member 16, medially located. The members 14, 15 and 16 are respectively provided with transverse central bores 14^a, 15^a and 16^a, and the male member 16 of one unit is adapted to enter the space between the members 14 and 15 of an associated unit. The transverse apertures 14^a, 15^a and 16^a are adapted to register and provide bearings for a pivot pin 17.

The elements 14 and 15 are supported by webs 14^b and 15^b, and have longitudinally extending rails 14^c and 15^c, and the element 16 is supported by a web 16^b, said element 16 being provided with a rail 16^c which extends longitudinally, medially of the rails 14^c and 15^c. Reinforcing ribs 14^d and 15^d strengthen the rails 14^c and 15^c, while a rib 16^d performs the same function relative to the rail 16^c.

The sprocket wheel with which the improved track is associated, is provided with a double row of corresponding teeth, and the rails 14^c and 15^c are adapted to bear on the periphery of the wheel outside the teeth, while the rail 16^c bears on the periphery between the two rows of teeth.

When the units are assembled, the end 11^a of one unit overlaps the end 11^b of a contiguous unit, the notch or recess 13 providing clearance for the web 16^b. The bearing of the web 16^b against the root 13^a of the recess 13 prevents upward buckling of the ground engaging leg of the track, thereby increasing the traction power.

Recesses 18 are provided in the outer faces of the female members 14 and 15, for the purpose of receiving the ends of cotter-pins 19 which retain the pivot pin 17.

It is obvious that an endless link track constructed substantially as above described, is durable and smooth running and therefore

highly efficient, and while I have described a preferred form of my invention, I am not limited to the precise details as set forth, but I desire to avail myself of such variations and changes as come within the scope of the appended claims.

What I claim is:

1. An endless link chain track comprising a plurality of articulated link sections, each link being provided with a tread plate and an upstanding male hinge member and two female members, rail members extending longitudinally from the female members, and a third rail extending from the male member medially of the first named rails and spaced therefrom, and journal pins connecting the male member of one link and the female members of an adjoining link.
2. An endless link chain track comprising a plurality of articulated link sections, each link being provided with a tread and a male hinge member and two female members, rails extending longitudinally from and in a plane with the top of the female members, and a third rail extending from the male member in a plane with the top thereof and medially of the first named rails and spaced therefrom, and strengthening webs from said rails to the tread plate.
3. A link section for endless chain tracks comprising a tread plate with three upstanding rail web portions cast integral therewith, one of said rails extending longitudinally, medially from one end of said tread plate, the other two rails extending longitudinally from the opposite end of said plate and spaced from the first named rail on opposing sides thereof, female hinge elements formed on the two outer rail members, and a male hinge element formed on the medial rail member.
4. A link section for endless chain tracks comprising a tread plate having a recess formed medially in one end thereof and two upstanding rail web portions cast integral therewith, said rail portions provided with female hinge elements and extending longitudinally of the tread plate, spaced laterally from said recess, a third rail web portion cast integral with the tread plate, provided with a male hinge element and extending longitudinally from the opposite end of said plate between the two rail portions first named and in alinement with the recess.
5. An endless link chain track comprising a plurality of articulated link sections, each link being provided with a tread plate and an upstanding male hinge member and two female members, rail members extending longitudinally from the female members, a third rail extending from the male member medially of the first named rails and spaced therefrom, a journal pin connecting the male member of one link and the female members of an adjoining link, and retaining elements connected with the ends of said journal pins.
6. An endless link chain track comprising a plurality of articulated link sections, each link being provided with a tread plate and an upstanding male hinge member and two female members, rail members extending longitudinally from the female members, a third rail extending from the male member medially of the first named rails and spaced therefrom, a journal pin connecting the male member of one link and the female members of an adjoining link, and cotter-pins in the ends of the journal pins, recesses being provided in the outer faces of the female members for locking said cotter-pins.

In testimony whereof I affix my signature.
ALBERT V. RACKSTRAW.
